UNITED STATES PATENT OFFICE.

JAMES A. MOULD, OF MILWAUKEE, WISCONSIN, ASSIGNOR TO M. B. M. MANUFACTURING CO., OF MILWAUKEE, WISCONSIN.

POWER-DRIVEN CULTIVATOR.

Application filed September 21, 1922. Serial No. 589,563.

To all whom it may concern:

Be it known that I, JAMES A. MOULD, a citizen of the United States, residing at Milwaukee, county of Milwaukee, and State of Wisconsin, have invented new and useful Improvements in Power-Driven Cultivators, of which the following is a specification.

This invention relates to power driven cultivators.

10 The general objects of this invention are to provide a successful motor driven cultivator having handles to be grasped by a person walking at the rear thereof and which can be properly guided and controlled by a 15 person in such position.

Small power units for two wheeled machines, have been used for various purposes, and attempts have heretofore been made to apply such units to hand guided cultivators, 20 but so far as I am aware, no such cultivators have gone into general use for the reason that the requirements for a successful cultivator have not been understood. Such requirements are quite different from those 25 applicable to other small motor driven, hand guided machines and some of them may be stated as follows:—

The machine must be sufficiently narrow 30 and the parts so organized as to make it easy or possible to guide the cultivator between rows of growing vegetables in a manner to avoid injury to the plants. The cultivating tools should be so disposed with reference to the wheels as to give the wheels 35 maximum mechanical advantage in holding the tools against lateral thrusts when such tools act upon stones, clods, or hard earth surfaces, thereby to render the guiding of the machine comparatively simple.

40 The weight of the machine should be so nearly balanced upon the wheel supported axle and so disposed with reference to the cultivating tools, as to make it unnecessary for the operator to put any great amount of 45 pressure upon the handle and to allow him to give substantially his entire attention to the guidance of the cultivator.

The heat generated by combustion in the 50 engine should be directed away from the operator and such heat should be utilized to some extent to warm the fuel prior to its introduction into the engine.

In hand guided, power driven cultivators, 55 the use of air cooled engines are virtually essential in order to avoid excess weight,

and the air currents developed in cooling such engines should be caused to follow a course best suited to prevent dust and dirt from settling upon the engine and power transmitting mechanism or from getting in to the bearings. 60

The power unit in its entirety should be so organized that removal of parts for the purposes of cleaning or repairing may be accomplished with facility. Furthermore, 65 simplicity, strength, and durability of structure as well as compactness of design, are of the utmost importance.

It is therefore the object of this invention 70 to provide a cultivator embodying features that will satisfy, to the fullest possible extent, all of the above stated requirements and to provide at the same time a thoroughly reliable and satisfactory machine for the 75 described purposes.

An embodiment of the invention is shown in the accompanying drawings, in which:—

Fig. 1 is a longitudinal sectional view of the cultivator.

Fig. 2 is a transverse sectional view, the 80 section being taken on the line 2—2 of Fig. 1, and the driving wheels being shown in full.

Fig. 3 is a schematic view of the control 85 mechanism for the clutch.

The cultivator comprises a body portion formed of a main casing, indicated generally at 1, which houses the driving mechanism, clutch, and associated parts.

The axle shaft 2 is preferably journaled 90 in this casing and the driving wheels 3 are rigidly secured thereto. At the rear upper portion of the main casing the engine cylinder 4 is mounted and is encircled by a jacket 5 which is spaced a material distance 95 from said cylinder, and forms an air passage leading downwardly along the engine cylinder and between the walls 7, which support the fuel tank 8, to the fly wheel 11, the latter being partially enclosed by the passage walls 100 10 and 10^a. A deflector wall 10^b depends from the fuel tank 8 between the passage walls 7 and directs air downwardly toward the axis of the fly wheel and around the reduced cylinder portion 9 of the main casing. The fly wheel is provided with vanes or flanges 12 which act as fan blades within the housing 10^a to deliver air outwardly or centrifugally from beneath the fuel tank as indicated by the arrows in Figure 1, the 110

105 housing 10^a to deliver air outwardly or centrifugally from beneath the fuel tank as indicated by the arrows in Figure 1, the 110

air being thus drawn by suction downwardly along the engine surfaces to cool the engine, and also utilized along the under side of the fuel tank to warm the fuel therein. The function of the wall or wall portion 10^a is to prevent the air from being thrown downwardly in a manner to disturb loose particles of earth and develop a dust cloud in advance of the machine. Thus, in addition to the provision of a construction adapted to take cooling air from an altitude where it will ordinarily be free of dust, I also take precautions to prevent dust from being stirred up by air expelled from the machine.

Within the cylinder 4, the piston 13, is mounted and is connected by means of a pitman 14 with the crank pin 15, such crank pin being rigidly secured within the crank plate 16. The crank plate 16 is secured by means of a taper fit upon the engine shaft 17, such crank plate being provided with a reduced forward portion 18. Roller bearings 19 are mounted between this reduced portion and a suitably bored portion formed in a thickened portion 20 of a transverse web provided in the main casing. The forward portion of the engine shaft is carried upon roller bearings 21 mounted within the reduced cylinder portion 9 of the main casing, and it will be noted that the two bearings for the engine shaft are mounted upon opposite sides of the axle shaft 2, and that the engine cylinder and associated parts are mounted upon the opposite side of the main axle shaft 2 from that upon which the fly wheel is located. The forward portion 22 of the engine shaft may be square or otherwise shaped to receive a detachable crank and such portion is protected by means of a sleeve 23 bolted to the forward face of the fly wheel 11.

The drive mechanism for operatively connecting the engine and axle shaft comprises a worm 24 formed upon, or mounted upon, the engine shaft 17 and a corresponding worm wheel 25 loosely mounted upon the axle shaft 2. This worm wheel is provided with jaws or clutch faces 26 which are adapted to cooperate with corresponding jaws 27 formed upon a clutch member 28 loosely splined upon the axle shaft 2.

The control mechanism for the clutch comprises an arm 29 secured upon a rock shaft 30, (see Fig. 3), and provided at its forward upper end with a pin 31, such pin riding loosely within a groove 32 formed in the clutch member 28. The rear portion of the shaft 30 is provided with an arm 33 extending substantially at right angles to the arm 29. This arm 33 is connected by means of a link 34 with one arm 35 of a bell crank lever, the other arm 36 of which is connected by means of an elongated rod 37 with a hand or finger control lever 38 mounted within easy reach of the operator's hand.

The cam shaft 39 is driven by means of reduction gearing 40 from the engine shaft 17 and operates the valves 41 and 42 of the engine by means of rods 43 and levers 44. A convenient way of forming this cam shaft 70 is to provide a relatively small rear bearing end 45 and a relatively larger forward bearing end 46 so that such shaft may be slipped rearwardly into position. The shaft is thereafter retained in position by means of the 75 set screw 47.

It will be noted that the casing for the engine and driving mechanism comprises essentially two main portions, one of which is in communication with the shell or casing 80 around the engine cylinder and with the fan-like fly wheel. The other portion of the casing is oil tight and carries the driving mechanism. Means are provided for throwing the oil upwardly against the rotating 85 crank plate 16 and such means may comprise a roller 48 suitably carried in the lower portion of the crank case and in frictional engagement with the crank plate 16 as may be seen from Fig. 1.

The lower portion of the casing has downwardly extending members 49 to which are bolted plates 50 provided with right angle faces. The lower portion 51 of these plates each carries a forwardly extending arm 52 95 which is secured in adjusted position by means of a bolt 53 passing through a bottom binding washer 54 and suitably clamping the member 52 between such washer and the portion 51. The forward portion of the bars 100 52 carry the cultivator blades 55 which may be secured in any adjusted angular position with respect to the bars 52 in a manner similar to that just described for the rear portion of such bars.

It is desirable to have the magneto 56 outside of the main casing and this mounting is secured by the novel arrangement described herewith. The magneto 56 is mounted upon a shelf 57 externally of the main casing and has its shaft 58 in alignment with the engine shaft 17. The end of the shaft carries a relatively light crank arm 59 which engages the crank pin 15 in any suitable manner, as for example, by engaging a relatively small projecting portion of such pin as shown in Fig. 1.

The entire device is guided by means of a pair of arms 60 bolted at their forward lower ends to projections 61 extending from the main framework or casing and provided at their rear ends with grips or handles 62.

It is particularly to be noted that the cultivator blades or tools 55 are positioned between the driving or tractor wheels 8 125 directly beneath the power unit and slightly to the rear of the vertical plane passing through the axis of the axle shaft 2. Such construction enables the wheels to resist any side thrust of the cultivator that may be 130

caused by the cultivator blades coming into contact with stones or other hard materials. Furthermore, this construction provides a relatively great leverage for the operator 5 over the blades and brings the tools sufficiently close to the steering axis of the machine as to obviate the probability of uprooting plants during ordinary turning movements required in following a row.

10 The mounting of the engine proper directly above the cultivator tools positions the weight thereof in a manner to render it of assistance to the operator in keeping the tools in the ground.

15 From the foregoing description and drawings, it is therefore apparent that a hand guided power driven cultivator has been provided which embodies all of the requisite qualities for a successful machine.

20 I claim:

1. In a power driven, hand guided cultivator, the combination with an axle shaft having tractor wheels secured thereon, of an internal combustion engine having power 25 transmitting mechanism for operating said axle shaft and clutch mechanism for putting said mechanism into or out of connection with the power shaft, a casing enclosing said power transmitting and clutch mechanism, a fly wheel for said engine positioned to the front of said axle shaft, and a fuel tank supported from the casing above the axle shaft and fly wheel.

30 2. In a power driven, hand guided cultivator, the combination with an axle for the cultivator, of an engine supported from the axle and positioned to the rear thereof, a fly wheel for the engine supported from the axle and to the front thereof, and a tool carrier adapted to support a cultivating tool directly beneath the engine and rearwardly 35 of the axle shaft.

35 3. In a power driven, hand guided culti-

vator, a pair of spaced tractor wheels, an engine supported therefrom at the rear 45 thereof, a fly wheel for the engine supported from the wheels at the front thereof, a fuel tank supported from the tractor wheels; said engine, fly wheel and fuel tank being supported from the tractor wheels in substantially 50 balanced relation thereto; an air propelling fan on the fly wheel, and means for directing air downwardly about the engine, into contact with the fuel tank and outwardly through the fan and away from the 55 ground beneath the cultivator.

4. In a device of the character described, a housing, an axle journaled therein and projecting laterally thereof, wheels carried by said axle, a gear concentric with said axle, 60 a crank shaft in direct driving connection with said gear, an engine cylinder and a piston operatively connected with said crank shaft upon one side of said axle and a fly wheel upon the other side of said axle, 65 whereby said device is substantially balanced against rotation about said axle from its normal operative position.

5. In a device of the character described, the combination with a pair of wheels and 70 an axle, of a housing provided with bearings for said axle, a crank shaft disposed in said housing transversely of said axle, said housing being provided with bearings for said crank shaft upon opposite sides of said axle, 75 intermeshing gears concentric respectively with said crank shaft and said axle, an engine cylinder supported from said housing adjacent one of said crank shaft bearings and a fly wheel mounted upon said crank shaft adjacent the other of said crank shaft bearings, said housing being substantially balanced against rotation about said axle 80 from its normal operating position.

JAMES A. MOULD.
